UNITED STATES PATENT OFFICE

2,602,628

FLUID TRANSFER SYSTEM AND APPARATUS

Wilfred J. Turenne, Fayville, and Carl W. Walter,
Holliston, Mass.

Application July 26, 1946, Serial No. 686,572

13 Claims. (Cl. 251—24)

1

The present invention relates to the handling of fluids, with special reference to preventing contamination or unintended modification thereof. While pertinent to various fields wherein fluids are to be collected, examined, treated or otherwise utilized, it finds important application in medical and surgical practice, as well as in general laboratory work, as in hospitals, testing laboratories and the like. Thus for example the method and means of the invention are useful in blood collecting and servicing and the various phases of blood banking, also in connection with intravenous and other injections, and for bacteriological investigations of any kind, as in checking milk supplies, testing water supplies, and analogous health fields.

Within the general objects as above indicated, the invention more particularly affords improved methods and means whereby the particular fluid may be introduced into a container and retained in sterile condition, with all or any portion of the container content available for investigation or use, without danger of contamination either of the fraction removed or of that remaining in the container. More specifically, the invention provides for taking samples of a fluid into a completely closed system without contacting air or any surface which has not been sterilized, and for delivering from such system specimen quantities of the collected fluid as desired, with assurance that the original condition has been preserved, as to bacteriological and other content, except for changes as may be inherent in the nature of the fluid or effected by deliberate treatment thereof.

In the drawings illustrating by way of example one embodiment of means of the invention and whereby the methods thereof may be practiced:

Fig. 1 shows in elevation a collection and storage unit or assembly including a typical container;

Fig. 2 is a vertical section, upon a larger scale, through the closure and inlet-outlet mechanism as at the upper portion of Fig. 1, the valve being closed;

Fig. 3 is a top plan of the valve assembly as in Fig. 2;

Figs. 4 and 5 are opposite side elevations of said valve assembly, respectively as if looking from the left and from the right at Figs. 2 and 3;

Fig. 6 is an elevation of the clamp or holder looking from the direction as in Fig. 2 or from the left in Fig. 5, the valve proper being demounted;

Fig. 7 is a horizontal section on the line 7—7 of Fig. 6, looking down;

Fig. 8 is a vertical section corresponding to a portion of Fig. 2 showing the valve open;

Fig. 9 is a side elevation, with parts in section, of the main body of the valve assembly, demounted and open; and

2

Fig. 10 is a perspective view of the valve proper. Referring first to Fig. 1, the apparatus as a whole as there illustrated comprises a container 10 shown as a flask, jar or the like, having a neck and mouth 11 equipped with closure means adapted for hermetic sealing. The container closure as illustrated comprises a rubber or other resilient bushing 12 centrally apertured at 13 and having an integral skirt 14 for turning down into gripping relation to the outer wall of the neck 11, below a bead 11' at its upper end. Cooperating with the bushing is a metal or other stopper indicated generally at 15 having a central stem 16 with an external venting channel 16' and a cap portion 17 shaped and proportioned substantially as illustrated to seat on and enclose the bushing and its downturned skirt. These container and closure elements as illustrated are of the type disclosed and claimed in Walter Patents Nos. 2,116,132 and 2,228,936, these being especially suited to the present purposes. In various of its aspects, however, the invention is equally applicable to other forms of closable containers.

The steel or other stopper 15 in this instance is further provided with a central passage 18 extending through its stem 16 and through a projecting nipple 19, affording communication with the interior of the container 10. The present invention is particularly adapted for use in association with an inlet-outlet connection for a container, such as the nipple 19, and comprises novel flow-controlling or valve mechanism whereby fluid may be entered into and withdrawn from the otherwise sealed container, without contaminating contact or exposure of the fluid.

Referring now more particularly to Figs. 2 to 10, the flow-control or valve assembly as a whole comprises a valve unit V, seen in section in Figs. 2 and 8 and separately in Fig. 10 and a clamp or holder C in which the valve unit is removably positioned.

Noting particularly Figs. 2, 5, 8 and 10 and considering first the valve unit V, this is an integral one-piece device molded, cast or otherwise formed of a resilient and compressible material such as natural or synthetic rubber or a rubber-like composition. In practice we have employed for the purpose gum rubber and compositions having similar general properties, as to elasticity, heat resistance and others. This valve unit or device V includes a generally tubular and cylindrical body 20, adapted for mounting on a tubular connection as herein represented by the nipple 19 of the cap 15. At one end of the body is a solid disk-like flanged head 21. Within the valve body and opening at its other end is a nipple-seating longitudinal passage 22 leading to a valve chamber 23 having a lateral generally cylindrical wall 24 provided with a lateral port 24a at the inner end of an integral tubular connector piece 25 having a through passage 25a leading from the port 24a. The outer

end of the lateral connector 25 may be beaded as at 25b.

On the valve body, spaced opposite the longitudinal passage 22, is a solid transverse wall member 26 providing a closed but flexible end or top wall for the valve chamber 23. At the inner face of this top wall 26, centrally of the valve chamber 23 and axially opposite the inner end of the passage 22 is the valve proper 27. It comprises a tapered valve plug or disc, of the same material as the device as a whole and integral with the top wall 26. At the outer face of the top wall 26 and in effect a continuation of the valve 27 and of said wall is a stem 28 preferably somewhat less in diameter than the underlying cylindrical chamber 23; see particularly Figs. 2 and 8. It is integrally joined with the head 21 at the upper end of the unit. Thus the chamber top wall 26 and the parts 21, 28 above it serve to support and guide the valve proper 27 and also, by reason of the elastic character and diaphragm-like structure, as a yieldable spring opening means therefor.

The valve body 23 desirably has at the end opposite the head 21 a peripheral flange 29 and the adjacent entrance end of the passage 22 may be flared as at 22a, Fig. 8. The inner end of this passage 22 also flares as at 23a and merges into the valve chamber 23 so as to define, with the nipple 19 in the illustrated example, a tapered seat for the disc or plug constituting the valve proper 27. In some instances the tubular connection such as the nipple 19 may terminate below the valve chamber, the valve disc then seating directly onto the self-material of the unit at the upper end of the passage 22. The tubular portion of the valve body 20 between the end flange 29 and the lateral wall 24 of the valve chamber desirably is of somewhat reduced outside diameter, for cooperation with the clamp or holder now to be described.

Such clamp or holder, designated generally at C, is of metal or other rigid construction. It includes a yoke-like vertically movable valve support and positioner 30 having horizontal upper and lower arms 31, 32 connected at one side as at 33 in spaced relation to receive the valve-supporting head 21 between them. The lower arm 32 has a slot 34 leading in from the side opposite the connection 33 and rounded at the closed end, centrally of the arm 32, for there embracing and positioning the valve stem or neck 28.

The upper arm 31 of the support element 30 has a central aperture 35, Figs. 2, 5, 8 and 9, opposite and smaller than the valve head 21 and countersunk at the inner end to seat a presser disc 36. The latter has swiveled supporting connection at 37 at the lower end of a valve-operating or control screw 38, the projecting end of which is squared or otherwise formed as at 39 to receive a key or other implement for turning it; Figs. 2 to 6 and 9.

The clamp or holder element C further comprises a clamping and guiding frame serving the multiple purpose of positioning and guiding the valve-support 30, adjustably supporting the valve control screw 38-39 and the valve-support 30 in effect hung thereon, and clamping the entire valve and frame assembly in operative position with reference to the passage to be controlled, herein the passage 18 in the nipple 19 of the stopper 15.

This frame section of the clamp C comprises a top plate 40 having a central threaded aper-

ture 41, see Fig. 3, in which the control screw 38 is engaged. The top plate 40 has opposed pairs of lateral ears, seen at the top and bottom in Fig. 3 pivotally supporting a pair of similar but oppositely disposed uprights or side members 43, seen in closed position in Figs. 4 and 5 and shown open and with the valve unit V removed in Fig. 9. These uprights 43 provide vertical guides and positioners for the valve slide 30, the adjacent side edges of both arms 31, 32 of which are recessed as at 31a, 32a, Figs. 6 and 9, to receive the uprights in the closed position of Figs. 4 and 5.

The lower ends of the uprights 43 are formed with cooperative oppositely disposed clamping feet or yoke-like clamp members 44, 44, each presenting a half portion of a collar-like enclosure for the basal part of the valve body 20. As best seen in plan in Fig. 7 each clamping foot 44 has a semi-circular recess 45, respectively in opposed matching relation. Thus the clamping feet 44 when brought together act as jaws adapted to grip and compress the valve body, so securing and sealing the entire assembly in installed position. Referring particularly to Figs. 4, 5, 7 and 9, each clamp foot 44 has two abutitive faces 46 and 47, one at each side of the corresponding upright side member 43. Both faces 46 and 47 of each foot 44 are beveled or formed at an angle to the axis of the valve, with an opposite inclination at the two sides of the given foot 44. These inclined faces 46, 47 are reversely arranged on the respective feet 44, the face 46 of one opposing the face 47 of the other. Thus the jaw-like feet in effect break joint relative to each other at the two meeting side portions and meet along oppositely inclined planes at said two sides. Pinching of the valve body 20 is thus obviated, as again noted later herein.

The clamping feet or clamp halves 44 are provided with means for locking them in gripping relation to the body of the resilient valve element V, as in Figs. 1 to 5, 7 and 8, with capacity for ready release for removing the assembly from a container or from the closure thereof, and for opening to a position as in Fig. 9 for demounting the valve unit V from the clamp C. Accordingly each clamping foot 44 has a pair of apertures 48 and 49, one at each side of the half-round recess 45 and herein centrally of the respective inclined faces 46 and 47, in matching alignment on the two feet or jaws 44 when the clamp is closed; see particularly Figs. 4, 5 and 7. Retractable mounted in and cooperating with the aligning apertures of the two feet 44 is a pair of clamp screws 50, 50. Each screw 50 is slideable and rotatable in one clamp foot 44 and is threadably engageable in the opposite foot 44. With the clamp C closed the two screws 50 are projectible across from one to the other of the clamp halves to lock them together.

While both clamp screws 50 may be movably mounted on the same clamp half 44 and threadably engageable with the other, preferably and as illustrated one screw 50 is carried by one clamp half, when the clamp is open as in Fig. 9, and the other screw 50 remains with the opposite clamp half. As seen in Fig. 9, each clamp screw 50 includes a reduced shank 51, a non-round or other operating head 52 at one end and a threaded portion 53 at the other end, with an annular shoulder or stop 54 between the latter and the shank. Accordingly herein the described aperture pairs comprise for each clamp half 44 a non-threaded aperture 48 and at the other side of the

same clamp half a threaded aperture 49. The non-threaded aperture 48 of one clamp half aligns with the threaded aperture 49 of the other. The corresponding clamp screw 50 is inserted through the given non-threaded aperture 48, with the threaded end 53 foremost, the operating head 52 defining the inserting limit. As seen at the lower left in Fig. 9 a retaining pin 55 on the corresponding clamp half 44 projects laterally into the non-threaded aperture 48 forming a retraction limit stop to engage the shoulder 54 of the particular screw 50, holding it against accidental withdrawal and possible loss but leaving it free for axial and rotative movement in the non-threaded aperture 48.

At the given side of the clamp C as a whole the aligning aperture 49 of one clamp half 44 is internally threaded for coaction with the threaded end 53 of the corresponding clamp screw 50 movably held in the non-threaded aperture 48 of the opposite clamp half. Hence when the two portions of the clamp C come together the two clamping screws 50 automatically align with the respective threaded receiving apertures 49 and may readily be turned up into locking position by a key or other tool applied to the manipulating screw heads 52.

Assume now that a valve unit V, Fig. 10, has been installed in the clamp unit C, Fig. 9, by laterally entering the valve head 21 between the upper and lower arms 31, 32 of the valve positioner 30 and sliding the valve neck 28 into the open slot 34 therefor in the lower arm 32; see particularly Fig. 5. The hinged uprights or side pieces 43 of the clamp C automatically assume a loosely enclosing engagement about the lower part of the valve body 20. If desired the clamp screws 50 may then be turned up to the extent of a thread or so from one into the opposite clamp half 44, to keep the parts together pending use.

When a valve-and-clamp assembly is to be installed on a container the clamp screws 50 if previously tightened are backed out to allow the valve body 20 to assume its normal uncompressed diameter. The resilient valve unit V may then be thrust down over the nipple or like connection 19 of the container. In the illustrated example the base flange 29 of the valve seats in sealing relation at the top wall 11 of the container stopper 15 having the connector nipple 19 thereon. The latter herein has a flared or beaded outer end 19a, Figs. 2 and 8, and is of a length to enter the chamber 23 of the valve, directly opposite the taper plug or valve proper 27, in position to afford a seat therefor.

The semi-circular recesses 45 of the clamp members 44 are of somewhat less diameter than the valve body 20 in the normal free condition of the latter. Accordingly when the clamp screws 50 are turned up to bring the clamp halves 44 toward or into mutual contact the valve body is compressively gripped in tight sealing engagement with the nipple. The enlarged upper end 19a of the nipple, Figs. 2 and 8, then prevents axial displacement of the valve and clamp assembly.

As previously noted the jaw portions of the clamping feet or members 44 have their meeting faces 46, 47 in angular relation to a plane containing the valve axis, and at different directions of inclination at the two sides of the clamp C. Thus the region of approach or actual contact of the opposed faces of the clamp members is distributed in both the circumferential and the axial directions relative to the re-

silient valve body 20, and herein oppositely with respect to the diametrically opposite sides thereof. Accordingly the angular beveled and offset cooperating faces 46, 47 of the clamp halves 44 approach each other in non-parallelism to the valve axis. Hence they tend to cam the resilient material of the valve element away from pinched engagement between the closing clamp parts, affording minimum opportunity for it to be extruded into the decreasing space between the closing clamp. Consequently the entire circumference of the valve body is compressively reduced symmetrically with maximum sealing efficiency.

It will be understood that the lateral outlet or inlet element 25 of the valve unit may be of any convenient length and may itself be formed as an integral or other portion of a flexible tubing through which the fluid is to be withdrawn from or admitted to a container such as 10, Fig. 1. In the example of the drawings the outlet-inlet piece 25 is represented as of adequate length for convenient access and manipulation when the valve unit V is installed in the clamp C, permitting a metal, plastic or other connective tube, needle or the like 60, Fig. 2, to be inserted or removed without disturbing other parts. A compressible ferrule 61, Figs. 2 and 10, may be provided on the lateral outlet-inlet piece 25 for gripping and sealing any inserted connection, and for instantly compressively closing and sealing the piece 25 upon removal of the connection, so affording auxiliary closure for the container and valve system.

From the foregoing description in connection with the drawings it is apparent that the wholly self-contained valve and closure of the invention, wherein the valve proper is integral with its supporting and guiding parts, provides for handling fluids with minimum opportunity for contamination.

The closure and valve means of the invention is particularly useful in blood collection and servicing and in connection with intravenous injections but is generally applicable wherever fluid samples are to be passed to or from a completely closed system out of contact with non-sterile air. The device affords a vacuum-proof seal, again noting in this connection the full circumferential engagement of the clamp C around the valve body 20, also the slanted joint of the clamp which keeps the rubber or rubberous material from oozing into the joint and making a leak. The valve member proper 21 is capable of maintaining a vacuum in the associated container, so that to open it may require actual pulling away from the seat as at 19a or 23a. In a sense, and particularly when the receiving nipple 19 does not enter the valve chamber 23, there is no fixed seat separate from the integral valve material. The valve device as a whole is completely packless.

By reason of the rigid frame or clamp C and the control screw 38 the valve is adjustable and is operable as a metering device. As noted in connection with the lateral port tube 25 and the ferrule 61 therefor the valve device provides a plural seal, the attaching tube 25 adapted to be squeezed tightly closed as the needle or other insert is disconnected. While in most instances this may be accomplished by hand, a pliers may be provided for the purpose, incorporated if desired with the same tool such as a key or wrench for manipulating the valve control screw 38 and the clamp screws 50. One such combined implement T is shown at the upper right in Fig. 1 and is comprised in the apparatus as a whole.

While the control screw 38 and also the clamp screws 50 may have manipulating finger pieces, their construction and arrangement for tool operation as by a key, wrench or the like T, whether external or of the Allen or socket type, obviates tampering.

The rubber or rubberous valve unit V, such as shown separately in Fig. 10, is expendable, in the sense that it may economically be used but once and then discarded, doing away with all problems of sterilization for reuse. The simple integral structure of the valve and the inexpensive material appropriate therefor make for such expendability. As stated, by reason of the vacuum-proof and vacuum-operative character of the valve it is especially adapted for collecting blood from donors into a sealed and evacuated container forming part of a completely closed system in which the valve is incorporated. In such instance, as represented in Fig. 1 the collecting apparatus in addition to the container 10 equipped with the valve and clamp assembly V-C of the invention requires only the adequate length of flexible tubing 65 one end of which is connected as by the tubular insert 60 in the lateral port piece 25. The other end of the tubing is formed or provided with an intravenous needle 66 which may be permanently installed as the regular end element for the tubing, the needle being a simple one-piece member of relatively inexpensive character such that it together with the tubing 65 and the rubber valve unit V are expendable and may appropriately be discarded after a single use. Fresh unused tubing 65 is assumed to be supplied in sterile internal condition and the sterilized needle 66 is stored in mounted sterile condition as by insertion through a plug of sterile cotton 67 within a test tube 68.

Thus it is evident that the apparatus of Fig. 1 and the others constitutes a completely closed system, the container 10 adapted to be at least partially evacuated to present a negative pressure condition therein. With such apparatus at hand, in the collecting of blood, it is necessary for the operator merely to withdraw the needle from the protecting test tube 68 and immediately insert it into the donor in a single operation. By reason of the completely closed and vacuum-subject system a distinctly smaller needle may be used, since the negative pressure condition in the container permits the blood to be forced thereto through the relatively small lumen by the normal body pressure of the donor. In this connection it is noted that clean unused needle, tubing and valve members may be assembled to a container containing at least 1% of its volume of liquid. The assembly is sterilized preferably at 121° C. for 30 minutes with the valve open to permit escape of air and steam. After the sterilizer has cooled to say 100° C. at atmospheric pressure the valve is closed, effecting an hermetic seal. Condensation of the steam in the container creates a vacuum such as referred to.

It is further evident that the invention comprises in the closed system fluid transfer apparatus a valve and connector unit such as V which is a one-piece and preferably expendable rubberous body defining a valve chamber as at 23, angularly related passages 22 and 25a communicating with the chamber, a self-contained valve proper 27 internally self-carried on the chamber wall opposite the chamber end of one of the passages, herein the passage 22 for seating on the nipple or other rigid tube 19, and means in-

cluding the head 21 for oppositely applying force effective to close or to open the valve adjustably. The unit V as a whole is an integral mass. In use it is operatively associated with a holding and manipulating clamp such as the element C, forming with it a valvular coupling and flow-controlling assembly. When provided in the tool-operated form of the drawings, making tampering difficult, the apparatus of the system desirably includes at least one instrument such as illustrated by way of example at T in Fig. 1, it being understood that one or more such tools are to be supplied to the authorized person or persons, a given tool generally being universally applicable to any desired number of the clamp and valve assemblies for a like number of containers 10.

It will be apparent that the closed system for fluid transfer and the apparatus therefor as herein disclosed is equally applicable for controlled flow of the fluid in either direction. That is, the fluid may be collected into the container such as 10 from a supply, with complete avoidance of contact with non-sterile outside atmosphere, or it may be dispensed from the sealed supply in the container. An instance of collection is that of blood from a donor, as previously described. In such instance, and in the numerous other uses, the container may be partially evacuated or at sub-atmospheric pressure internally. In the reverse use of the apparatus, for dispensing from the container or otherwise transferring content therefrom, appropriate venting may be effected when desired as by retracting the stopper 15 so that the channel 16 of the stem is opened to atmosphere.

Our invention is not limited to the particular embodiment thereof illustrated and described herein, and we set forth its scope in our following claims.

We claim:

1. In a closed system for fluid transfer to and from a container, a container sealing closure having a tubular inlet-outlet nipple, a one-piece valve and coupling unit of resilient material having inlet and outlet passages, one passage engageable externally over and in sealed communication with the nipple and the other adapted for tubing connection, the valve and coupling unit further including a self-contained valve to close off and variably to open the passages interiorly of the unit, a clamp demountably assembled with the valve, and coupling unit and carrying adjustable valve-operating means, and manipulating means for the clamp and valve assembly, the valve and coupling unit being expendable and replaceable by a like fresh unit in the clamp.
2. For controlling fluid transfer, in combination, a rubberous valved coupling having a body with a through passage and an integral internal valve therefor, and a rigid clamp comprising opposed pivoted clamp members to embrace the rubberous body, a carrier plate to which said members are pivoted, means to lock the members in clamping relation, and threaded manipulating means on the plate for operating the valve.
3. A holding and manipulating clamp for a resilient rubberous valved coupling, the clamp comprising a carrier plate, opposed clamp members pivoted on the plate and having clamping portions to embrace the coupling, threaded operating means to clamp and to release the clamp members, a valve-operating member movably guided by the clamp members between the carrier plate and the clamping portions of said

members, and a manipulating element movably extending through the plate for controlling the operating member on movement in one and the opposite directions.

4. A holding and manipulating clamp for a resilient rubberous valve and connector unit, the clamp comprising a carrier plate, a pair of pendant opposed clamp members pivoted on the plate and having clamping portions to embrace one end of the unit, threaded operating means to clamp and to release the clamp members, a unit-supporting member movably guided by the clamp members between the carrier plate and the clamping portions, and a manipulating screw threaded through the plate and slidably and rotatively engaged with the supporting members for applying valve-closing force on screwing in one direction and valve-retracting force through the supporting member on screwing in the other direction.

5. A valve and connector clamp according to claim 4 wherein the threaded clamp-operating means and the manipulating screw are terminally provided with instrument engaging formations, together with instrumental means for manipulative connection at the engaging formations.

6. A tubing coupler, valve and operating assembly comprising an integral rubberous body having a through passage defined by an enclosing wall incorporating a valve seat between opposite ends of the passage, the body also having a valve proper movable to and from passage-closing position at the seat, and a demountable clamp for mounting said body with one end of the passage wall seated on a relatively rigid tubular connection, said clamp including opposed pivotally interconnected clamp halves presenting jaws having mating arcuate formations to enclose and compressively seal the seated passage end of the body to the tubular connection, means for releasably locking the jaws in such sealing relation, and operating means movably carried by the clamp and engaging an intermediate portion of the rubberous body to effect movement of the valve proper to and from passage-closing position.

7. An assembly according to claim 6 in which the jaws have mutually abutive faces at opposite sides of the respective arcuate formations, the faces being disposed at an angle to the axis of the jaw-enclosed passage wall.

8. An assembly according to claim 6 in which the jaws have mutually abutive faces at opposite sides of the respective arcuate formations, the faces being disposed at an angle to the axis of the jaw-enclosed passage wall and also being oppositely angularly inclined at the opposite sides of the respective jaws, whereby symmetrical compressive sealing reduction of the enclosed passage-defining body wall is facilitated.

9. For fluid transfer systems, an integral one-piece valve and coupling unit comprising a resilient rubberous body having a through passage with tubular connective inlet and outlet terminals, an intermediate portion of the passage defining a valve seat, and a valve proper of self-material internally carried by the resilient rubberous body opposite the valve seat for closing and opening coaction therewith under inward flexure and release of the carrying body adjacent the valve, together and in combination with an installing and operating clamp having jaw means for compressively sealing one passage ter-

5 minal about a relatively rigid tubular connection, and having adjustable operating means for applying and releasing valve-operating force to the rubberous body.

10. The combination according to claim 9 wherein the rubberous body and the operating means of the clamp are relatively constructed and arranged to impose closing force in one direction and to release and apply opening force in the opposite direction relative to the valve.

15 11. An expendable conjoint coupling and valve unit for closed fluid transfer systems comprising a resilient-walled body enclosing a central chamber having communicating passages for through closed conduct of fluid in one and the opposite directions alternatively, the juncture of one passage with said chamber defining a valve seat, a self-contained valve plug internally carried on the chamber wall opposite the seat, and a valve-operating stem externally carried on said wall and undercut for push-pull engagement by demountable manipulating means, said unit as a whole comprising an integral molded one-piece rubberous mass.

20 12. An hermetic sealing inlet-outlet tubing connection for containers comprising in combination a centrally apertured resilient bushing having a reducing portion receivable in the container mouth and an integral skirt for turning down into gripping relation to the outer wall of a container neck, a hollow nipple-forming stem snugly received in the bushing aperture and extending inwardly-outwardly thereof, said stem formed in the inwardly extending portion with an external venting channel and in the outwardly extending nipple-forming portion with a circumferential recess adapting it for clamped sealed coupling to a fluid conductor, and a flanged cap received over said stem and seated on and enclosing said bushing and its down-turned skirt.

25 13. An hermetic sealing tubing connection for containers comprising a hollow nipple-forming stem having at the inner end an axial venting channel, and at the outer end a circumferential formation adapting it for tight sealing engagement with a fluid conductor, and a substantially flat cap fixed on an intermediate portion of said stem and having a downturned peripheral flange, said intermediate stem portion and said peripheral cap portion shaped and proportioned for sealing engagement with inner and outer wall-embracing portions of a resilient container-neck-seated bushing with which the connection is designed to be used.
